(57) **CLAIM**

The ornamental design for a ring, as shown and described.

DESCRIPTION

FIG. 1 is an isometric view of a first embodiment of a ring, showing my new design;

FIG. 2 is a top view of a first embodiment of a ring. A bottom view is a mirror image of the top view; and,

FIG. 3 is a right side view of a first embodiment of a ring. The design is uniform around the ring.

The broken lines form no part the claimed design. Surfaces that include surface shading form part of the claimed design and any surface adjacent to broken lines that does not contain surface shading forms no part of the claimed design.

1 Claim, 2 Drawing Sheets
